CLAIM

The ornamental design for a combined monitor, video tape recorder and video camera, as shown and described.

DESCRIPTION

FIG. 1 is a top, front and right side perspective view of a combined monitor, video tape recorder and video camera according to our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, rear and left side perspective view thereof. The dashed lines illustrated in the drawing figures depict a strap and connections for handling the combined monitor, video tape recorder and video camera and which strap and connections form no part of the present invention.
